MOTION CHECKING OR SNUBBING DEVICE

Lester C. Frey, Cincinnati, Ohio, assignor to The American Laundry Machinery Company, Norwood, Ohio, a corporation of Ohio

Application August 7, 1939, Serial No. 288,692

11 Claims. (Cl. 38—25)

This invention relates to garment pressing machines and more particularly to a motion checking or snubbing device for the movable head member and its connected parts.

The object of the invention is to provide improved snubbing means which forms part of or is associated with the head closing fluid motor, doing away with supplemental or extra snubbing devices or attachments for the purpose and utilizing the motor not only as an actuator for the head itself, but also to control its motion in a manner to avoid shock and jar.

A further object of the invention is to provide a snubbing arrangement of the character described in which the operating piston of the head closing motor is made effective throughout its entire area for the major portion of the head closing stroke and effective over a reduced area during the latter part of its stroke to reduce the head closing force and thereby amplify the snubbing or cushioning resistance applied as an opposing force.

A further object of the invention is to utilize the head closing fluid pressure motor, by the application of controlling devices thereto, for cushioning or snubbing the motion of the head lever and its attached parts as they approach either end of the stroke, that is to say, in either the head closing or head opening directions.

Still another object is to provide an arrangement of this kind which is readily adjustable to vary the cushioning or snubbing effect.

Further objects of the invention are in part obvious and in part will appear more in detail hereinafter.

In the drawing, which represents one suitable embodiment of the invention, Fig. 1 is a side elevation of a pressing machine, with the head open, the control devices being illustrated diagrammatically and in section; Fig. 2 is a detail plan view, on a larger scale, looking at the parts in the direction of the arrows 2—2 in Fig. 1, parts being shown in section to illustrate interior construction; and Fig. 3 is an elevation, from the bottom in Fig. 2, parts being shown in section on the line 3—3, Fig. 2.

The drawing illustrates a conventional form of garment pressing machine and control, which of themselves form no part of the invention except as they are included in the combination and defined in the claims appended hereto.

The garment press illustrated is of the same general form shown, described and claimed in a prior patent, No. 2,082,913, for Operating and control mechanism for pressing machines, grant-

ed June 8, 1937, to John P. Singiser, to which reference may be had for a more complete description of the parts, if desirable or necessary.

As illustrated, the garment pressing machine comprises a suitable frame 1 on which is supported a vertically movable work support or bed 2 actuated by a lever 3 operated by a final pressure fluid pressure motor 4, the piston rod of which is connected to the lever 3.

In the upper portion of the frame is mounted the usual pivoted lever 5 carrying an upper pressing member or head 6, the rear arm of lever 5 being connected to the upper one of a pair of toggle links 7, 8, the lower one of which is pivoted at 9 to the stationary frame. 10 indicates the usual head opening tension springs and 11 the head closing motor, which is of the fluid pressure variety with its piston 12 working in a cylinder 13 and having a rod 14 extending out through one end of the cylinder and pivotally connected at 15 to the lower toggle link 8.

The control devices include two valve mechanisms, respectively marked 16, 17, valve mechanism 16 including a normally closed inlet valve 18, and valve mechanism 17 including a normally closed inlet valve 19 and a normally open outlet valve 20.

Valve 18 is on a rod 21 actuatable by the finger lever 22.

The casing of valve mechanism 17 is provided with an exhaust port 23 and its valves 19 and 20 are on a stem 24 actuatable by the finger lever 25. 26 illustrates the conduit communicating with a source of fluid pressure to supply motive fluid.

By depressing both of the finger levers 22, 25, one by each hand, fluid pressure is permitted to flow from the supply pipe 26, serially through the two valve mechanisms 16, 17 to the chamber within motor 11 on the pressure face of the piston 12, moving the same over and swinging the toggle mechanism and head lever from fully open toward closed position, until finally the knuckle of the toggle levers moves slightly beyond fully straightened position, with the lower toggle member 8 against the yielding kick back device 27. In this position of the parts the head is closed upon the bed, but without heavy pressure, ready for the application of final heavy pressure.

Final heavy pressure is produced by the final pressure motor 4, the flow of pressure to which is controlled by valve mechanism 28, including normally closed inlet valve 29 and normally open exhaust valve 30, both attached to a stem 31 actuatable by an arm 32 of a finger lever 33. 34 indicates an exhaust port.

When the head has been fully closed by operation of motor 11, the finger lever 33 is elevated in Fig. 1, moving over the valve mechanism 29, 30 and establishing communication from the supply pipe 26 to motor 4, the piston of which moves over and elevates the bed 2 against the now stationary head 6 and applying final heavy pressure. Of course, as soon as the bed begins to rise and apply pressure to the head, the fingers can be removed from the levers 22, 25. Ultimately the final pressure upon the work is maintained by a latch lever 35 held by a spring 36 in locking engagement with the lever arm 32, after the same is moved over, as described in the Singiser patent referred to. The press is released by forcibly depressing lever 33, which cams the lever 35 out of the way and permits the valve mechanism 28 to move to fluid pressure release position, evacuating motor 4, and permitting bed 2 to descend until, finally, the kick back device 27 throws the toggles 1, 8 back over dead center and the press opens under the influence of the tension springs 10.

The motion checking and snubbing device forming the subject matter of the present invention, insofar as it affects the closing stroke of the moving parts, includes a conduit 40 communicating at one end, at 41, with the far end of the cylinder 13 on the back face of its piston 12, in what may be called the inactive chamber of the cylinder, said conduit at its opposite end also communicating with the cylinder chamber at 42, at a point short of the end of the stroke of the motor piston. In other words, as the piston 12 moves along cylinder 13, and at just about the time when the head is, for example, two inches from the bed, said piston 12 passes by and exposes the port or opening 42.

The inactive chamber of the cylinder also communicates by a pipe 43 with an adjustable relief or vent valve 44 and a check valve 45 seating outwardly.

During the first portion of its stroke, until the piston 12 reaches the port 42, the fluid pressure supplied to the active chamber of the motor 11 is effective over the entire piston area and exerts the maximum possible head closing effect. The relief valve 44 is the only outlet for compressed fluid from the inactive chamber on the back face of the piston, and said valve 44 is adjusted to such area, by manipulation of its handle 46, that it will not materially hinder or retard advance of the piston during the first portion of its closing stroke, so that head closing movement proceeds in the normal way without retarding effect. However, as soon as the port 42 is uncovered, a supply of fluid pressure enters the pipe 40 at 42 and flows through said pipe and into the inactive cylinder chamber on the back face of the piston. Of course, this fluid pressure has escape through the relief port 44, but the area of said port is such as to choke free flow of the full fluid pressure effect. As the result, when the port 42 is passed, practically the full pressure of the fluid pressure supply is built up on the back face of the piston. Consequently, during the last two inches or so of head travel, piston motion is produced by fluid pressure, the net value of which is, due to the area of the piston rod, the differential in the areas on the two faces of the piston. Opposed to piston travel is the restriction now effective as a retarding force at the valve 44. The result is that the final travel of the head closing piston is checked and the head motion is effectively

snubbed and jar and shock are avoided and prevented.

Of course, so long as the two manuals 22, 25 are depressed, fluid pressure will escape through the valve 44, but in this type of control mechanism the manuals 22, 25 are released as soon as the final pressure motor 4 becomes active, so that further flow to the cylinder 13 is cut off and the fluid pressure therein is evacuated. Upon return of the piston 12 to its original position, when the head opens at a later stage of the cycle, air freely enters the inactive chamber on the back face of the piston through the inwardly opening check valve 45, as will be obvious.

Means is also provided for checking the motion of the parts during head opening movement. As illustrated, the pipe 47 coming from valve mechanism 17 to motor 11 communicates with the active chamber of said motor by way of a check valve 48 seating outwardly, so that full fluid pressure is quickly admitted to the cylinder past said valve. However, the pipe 47 also communicates with the active chamber and cylinder by way of a conduit 49 and an adjustable needle valve 50 (see Fig. 2).

When the manual 33 is forcibly depressed, to release the press by evacuation of final pressure motor 4, the head and its connected mechanism are moved to press open position first by the starting effect of the kick back device 27 and then by the effect of the tension springs 10, which cause the piston 12 to return to its original position, moving to the right in Fig. 2. Relief or evacuation of fluid pressure from the active chamber in the cylinder can only occur by way of the needle valve 50; and pipes 49 and 47, because the check valve 48 seats outwardly and is closed. Consequently by proper adjustment of the valve 50 a retarding effect may be produced upon press opening movement, slowing it down as much as may be desirable to avoid slamming or banging of the parts and consequently shock and jar. But the arrangement described offers no hindrance to press closing operation.

The motion checking mechanism described is of simple form, consisting of only a few standard simple valves and pipe sections connected directly to the press closing motor, and producing a snubbing effect by control of that motor instead of by the attachment of devices auxiliary or additional to the motor itself. Of course, it will be realized that these motion checking devices are practical and operative only because the motor 11 is merely used for press closing and not for pressure maintaining purposes, pressure being evacuated therefrom at the time when the press is maintained closed by the pressure in motor 4.

What I claim is:

1. A pressing machine comprising relatively movable head and bed pressing members, a cylinder and piston motor operatively connected to one of said members for closing the press, means operatively connected with the other of said members for producing pressure between said members, the cylinder chamber of said motor having active and inactive spaces on opposite sides of said piston, a pressure fluid supply to the active space of said chamber, and a passageway establishing communication between the active and inactive spaces of said chamber when the piston nears the end of its press-closing stroke.

2. A pressing machine comprising relatively movable head and bed pressing members, a cyl-

inder and piston motor operatively connected to one of said members for closing the press, means operatively connected with the other of said members for producing pressure between said members, the cylinder chamber of said motor having active and inactive spaces on opposite sides of said piston, a pressure fluid supply to the active space of said chamber, a passageway establishing communication between the active and inactive spaces of said chamber when the piston nears the end of its press-closing stroke, and means providing restricted venting for the inactive space of said chamber.

3. A pressing machine comprising relatively movable head and bed pressing members, a cylinder and piston motor operatively connected to one of said members for closing the press, means operatively connected with the other of said members for producing pressure between said members, the cylinder chamber of said motor having active and inactive spaces on opposite sides of said piston, a pressure fluid supply to the active space of said chamber, a passageway establishing communication between the active and inactive spaces of said chamber when the piston nears the end of its press-closing stroke, the inactive space of said chamber being provided with communication to atmosphere by way of a restricted opening and also by way of a check valve opening inwardly only.

4. A pressing machine comprising a pair of coacting relatively movable pressing members, a cylinder and piston motor having a piston rod operatively connected with one of said members for moving the latter to safe-closed position adjacent the other member, means for thereafter holding the pressing members in pressure engagement, means for supplying pressure fluid to the active face of said piston to cause a press-closing stroke thereof, said active face being of greater area than the inactive face on the piston rod side of said piston, said cylinder providing a chamber on the piston rod side of said piston preventing rapid loss of pressure fluid from said chamber, there being a port in said cylinder uncovered by said piston near the end of its press-closing stroke, and an open passageway providing communication between said port and the piston rod end of said chamber.

5. In a pressing machine of the type described having a frame, head and bed pressing members movable therein, a head closing motor having a closed cylinder and having a piston rod for closing said head and for placing a strut to hold said head in said frame against retrograde movement, having a motor for pressing said bed against said head when so held, means for supplying pressure fluid to said motors in the order of their naming and means for evacuating said first named motor after energizing said second named motor; snubbing means for said first named motor including a port in the wall of said cylinder uncovered by said piston near the end of its press-closing stroke, and a conduit providing communication between said port and the piston rod end of said cylinder.

6. The combination of claim 5 including a restricted vent in the piston rod end of said cylinder.

7. The combination of claim 5 including a restricted vent in the piston rod end of said cylinder, a check valve communicating between the piston rod end of said cylinder and atmosphere, said valve opening inwardly only, a restricted

vent at the other end of said cylinder, and a check valve in the pressure fluid supply for said first named motor, said last named check valve permitting flow toward said cylinder only.

5 8. A pressing machine comprising a pair of coacting relatively movable pressing members, a cylinder and piston motor for causing relative closing movement of said members, the cylinder chamber of said motor having relatively active and inactive spaces on opposite sides of said piston, means for supplying pressure fluid to the active space of said cylinder chamber for causing press-closing movement of said piston, said cylinder chamber providing a substantially fluid-tight inactive space, there being a port in said cylinder uncovered by said piston near the end of its press-closing stroke, an open passageway providing communication between said port and said inactive space, and means for slowly releasing pressure fluid from said inactive space, whereby pressure fluid admitted to said inactive space through said port retards the latter portion of the press-closing stroke of said piston.

9. A pressing machine comprising a pair of coacting relatively movable pressing members, a cylinder and piston motor for causing relative closing movement of said members, the cylinder chamber of said motor having relatively active and inactive spaces on opposite sides of said piston, means for supplying pressure fluid to the active space of said cylinder chamber for causing press-closing movement of said piston, said cylinder chamber providing a substantially fluid-tight inactive space, there being a port in said cylinder uncovered by said piston near the end of its press-closing stroke, an open passageway providing communication between said port and said inactive space, and the face of said piston toward said active space being of greater area than the face of said piston toward said inactive space, whereby pressure fluid admitted to said inactive space through said port retards the latter portion of the press-closing stroke of said piston.

10 10. A pressing machine comprising relatively movable head and bed pressing members, a cylinder and piston motor for causing relative closing movement of said members, means for supplying pressure fluid to one face of the piston of said motor for closing the press, means rendered operative by piston movement near the end of its press-closing stroke for supplying pressure fluid to the other face of said piston, and means for reducing the pressure of said fluid against said other face to less than the pressure of the fluid supplied to the first named face of the piston, whereby said piston will advance slowly during the latter part of its stroke in press closing direction.

11. A pressing machine comprising relatively movable head and bed pressing members, a cylinder and piston motor for causing relative closing movement of said members, means for supplying pressure fluid to one face of the piston of said motor for closing the press, means rendered operative by piston movement near the end of its press-closing stroke for supplying pressure fluid to the other face of said piston, and said other face of said piston having less effective area exposed to pressure fluid than said first named face, whereby said piston will advance slowly during the latter part of its stroke in press closing direction.
